UNITED STATES PATENT OFFICE

ADOLPH KRUEGER, OF NEWARK, NEW JERSEY, ASSIGNOR TO MARVEL SPECIALTIES CORPORATION, OF NEWARK, NEW JERSEY, A CORPORATION OF NEW JERSEY

WINDOW CLOSER

Application filed April 21, 1927, Serial No. 185,633. Renewed September 4, 1929.

This invention relates to a window closer which is adapted to be operated by rain, the rain which runs down the window pane being directed into a trip device which, in turn, releases a spring closing means which is put under increased tension when the window is opened. The device can be adapted to various forms of sashes but I have illustrated it as applied to a sliding sash. The device has in addition to an automatic means a manually operated means for tripping the spring means for closing the sash.

The closure is adapted to collect water from the window in sufficient quantity to operate the trip in short enough time to prevent any material damage by water entering an open window.

The device is illustrated in the accompanying drawings in which Figure 1 is a view of a window equipped with the closure. Figure 2 is an enlarged front view of the closure broken away to permit a contraction in the figure. Figure 3 is an end view of Figure 2 and Figures 4, 5 and 6 are sections taken on line 4 in Figure 2, showing various positions of parts in the setting and releasing of the device. Figure 7 is a top view, with the casing shown in section, of the parts illustrated in Figure 4. Figure 8 is a section on line 8—8 in Figure 7. Figure 9 is a perspective of a form of attaching means and Figure 10 is a perspective view of some parts of the tripping device to more clearly show their relative positions and their construction.

In the drawing the device is shown as adapted to close the sliding sashes of a window and I show the upper sash 10 and the lower sash 11. The device is shown as mounted under the lower rail of the upper sash and consists of a tube or barrel 12 which is held under the sash and against turning, one form being the pins 13 which are shown in Figure 2 which are fitted into plates 14 which are secured to the sash. The device is spring operated and when the sash is open the device is put under increased tension and for this purpose a flexible connection is secured to a suitable anchor which may be the window frame or it may be the other sash. This connection is usually, in the case of two

sashes, slid to the upper rail of the lower sash and is a flexible connection.

In the drawing I show a steel tape 15 on each side fastened as at 16 to the lower sash. This flexible connection is coiled around the shaft 17 which passes through and is rotatable in the body portion or case 12 of the closure and the spring 18 is put under greater tension when these connections 15 are pulled in the manner of a spring roller so that the spring 18 when released slowly coils up and pulls, by means of the rod 17, on the connection 15 and closes the sash or sashes, the spring 18 being secured at one end rigidly to the casing and may be secured as shown in Figures 2 and 3 by utilizing the inner ends of two of the pins 13 by passing the wire around them, the other end of the spring being secured to the barrel 19 which is secured to the rod or shaft 17 but has a limited sliding movement thereon to accommodate the elongation of the spring. One or both ends of the closure can be slid with a spring.

To hold the parts against premature return the shaft 17 is held by a ratchet 20 which, in turn, is held by a pawl in the form of a pin 21 on a plate 22, pivoted at 23 and held in position by spring 24 and this pawl 21 is released by a trip either manually operated or mechanically operated by the weight of water dripping from the sash.

To provide for a quick accumulation of water I arrange a gutter 25 extending for the length of the closure and inclined toward the trip which is usually at the centre in the housing 26. The gutter 25 projects so that it is directly under the outer edge of the upper sash, the water runs down the gutter on each side and is deposited in a small receptacle in the form of a bucket 27 which is pivoted as at 28 to the two side plates 29 and 30 and has a counter-weight 31 for returning it to position when it is released.

The receptacle 27, when weighted by the water in it descends and the pin 32 lifts up the lever 33 pivoted on the rod 34 which spans the space between the walls 29 and 30 and thus swings back the hook 35.

The hook 35 normally holds a pin 36 of a pivoted cam 37. The pin has a spring 38

secured to it at one end, the other end of the spring being shown as secured to a cross bar 39. When the hook 35 is swung back and releases the cam 37 the said swings forward on its pivoted pin 38 and pushes the extension 40 of the pawl 22 so as to release the pin 21 from the ratchet 20 and the spring winds up the connection 15 and the window slides to closed position.

20 This trip can also be manually operated by pushing on the finger-piece 41 on the end of a plate 42 which is slotted and mounted on cross pins 34 and 43 and this plate in turn engages the pin 36 to force the hook to open position against the influence of the weighted end or arm 33. This weight is sufficient to normally hold the hook against the influence of spring 38 as the said spring is arranged at an angle that makes it easy for the hook 20 35 to retain the pin 36.

When the device is to be re-set and the bucket 27 is in normal position, the window is opened and when this takes place the ratchet moves around with the shaft 17. 25 This ratchet carries a swinging plate 44 pivoted to the ratchet at 45 and thus carried around with it. The plate has a pin 46 which extends through a slot in the ratchet and has its end in the annular recess 47 in the ratchet. 30 (See Figure 8.) On the cam 37 is a pin 48 which extends through a slot 49 in the wall 30 and is in the path of pin 46 as it also extends into the recess 47. When the ratchet turns in a direction to wind up the spring 35 the pin 46 pushes the pin 48 which swings the cam around until the pin 46 clears pin 48. By this time the cam has been swung far enough to push the pin 36 down on the inclining end 50 of the hook 35 and the pin 40 36 is caught under the hook. When the direction of movement of the ratchet is reversed the pivoted plate 44 can swing to allow the pin 46 to ride over the pin 48.

Excess movement of the cam is prevented 45 by the engagement of the hooked extremity 51 with the cross bar 34.

I claim:

1. A window closer comprising a spring closing means, a connection operated by the closing means and connecting the closing means and a suitable anchor, the connection thus acting to put the means under tension when the window is open, a trip for releasing the closing means and a gutter to direct rain from the window to the trip to expedite the accumulation of water to operate the trip.

2. A window closer comprising a tube, a spring actuated rod in the tube, a flexible connection coiled on the rod, means for holding the rod when the spring is under a tension, a trip for releasing the holding means, said trip including a receptacle to receive water, and means on the tube for conducting water to the receptacle.

3. A window closer comprising a tube, a spring actuated rod in the tube, a flexible connection coiled on the rod, a pawl and ratchet for holding the rod when the rod is under spring tension, a trip for the pawl, 70 said trip including a receptacle for water, means for conducting water along the tube to the receptacle, and a finger piece for manually operating the trip.

4. A window closer comprising a spring closing means in a casing and arranged longitudinally on a window sash and shaped so as to direct water descending from the window to a point in its length, a trip arranged at said point, and a connection from the closing means to an anchor. 75

5. The combination with a pair of sliding sashes, of a spring roller on one sash, a connection from the roller to the other sash, and a trip for releasing the roller and constructed so as to receive water from the sash whereby it is actuated. 80

6. The combination of a pair of sliding sashes, a casing with a trough on the outside and secured at the bottom of the upper sash, a spring roller in the casing, a trip to receive water from the trough and to thus release the spring roller, and a connection from the spring roller to the lower sash so that the spring roller when released will close either 90 or both sashes. 95

In testimony whereof I affix my signature.
ADOLPH KRUEGER.
